HEAVY DUTY VISE

Newman M. Marsilius, Bridgeport, Conn.

Application February 4, 1939, Serial No. 254,547

7 Claims. (Cl. 90—62)

My invention relates to vises such as are adapted to be used on heavy duty milling machines for holding work thereon to be milled. It is adapted for extreme applications and is adapted to last indefinitely since the body is made of heavy semi-steel casting reinforced with hardened and ground wearing and guide plates.

The object of the invention is to provide a more substantial, durable and practical form of vise for attachment to machine tools than is now to be found on the market and one which is adapted to be attached upon a planer bed or a milling machine bed for securely holding a large variety of work pieces in position to be operated upon, to provide a vise whose body, front and rear jaws, nut and block are made from semi-steel castings, to provide a body that is reinforced on top side with indestructible hardened and ground wearing and jaw guide plates and further to provide jaw guide plates that are serrated to receive serrated blocks on rear jaw and nuts to prevent slipping.

The front and rear jaws and nut blocks are adjustable to provide extra large openings between jaws. A further feature is to provide for the removable attachment of a separate intermediate jaw, to provide two holding positions at one time.

These and other features of the invention are included in the accompanying illustrations of my improved vise as shown on the accompanying two sheets of drawing forming a part of this specification and upon which similar characters of reference denote corresponding parts throughout the several figures.

Fig. 1 shows a perspective view of my improved vise in an open position but not including the intermediate insertable floating jaw.

Fig. 2 shows a top plan view of the vise shown in Fig. 1 and including the intermediate, removable floating jaw not shown in Fig. 1.

Fig. 3 shows a vertical, longitudinal, sectional view through the length of the vise shown in Fig. 2 and taken on line 3—3 of that figure.

Fig. 4 is a perspective view of the left hand end portion of the vise as shown in Fig. 1 but including the central floating jaw and also shows an attachable jig fixture as used in drilling operations.

Fig. 5 shows a detached plan view of another form of jig fixture adapted to be used in lieu of that shown in Fig. 4, for multiple drilling operations, and

Fig. 6 shows a detached end view of the base of the vise.

My vise briefly comprises an elongated base having a pair of longitudinal T-slots extending through the upper portion thereof for the attachment and guidance of fixed and movable jaws. Upon this base is mounted four attachable parts comprising a supporting member for a clamping screw, a front movable clamping jaw operated by the screw, a rear jaw that is fixedly attached to the end portion of the vise opposite to that of the clamping jaw and a separate intermediate attachable center floating jaw which may or may not be used as desired according to the class and amount of work to be clamped, but which when used provides two separate jaw openings forming two holding positions to accommodate one or more pieces of stock to be milled.

The vise as shown in Figs. 2 and 3 includes in addition to its base three clamping jaws A, B and C and a fixed yoke D all of which are adjustably mounted on the base.

With further reference to the characters of reference marked upon the drawings, 10 represents the base of the vise which as shown is provided with ears 11 on opposite ends for its attachment to the bed of a milling machine, drill or other suitable machine tool, not shown. This bed as will be seen includes two longitudinal slots 12—12 that extend through the upper portion of the base from end to end. The top of the base 30 is further provided with hardened wearing and guide plates 13—13 on opposite sides and a similarly hardened intermediate plate 14 which are secured to the top central portion of the base by screws 15 as shown.

The under inner edge portions of these plates slightly overhang the upper side edges of the slots 12 to form of them T-slots to accommodate shoes 16 and blocks 17. The exposed under edge portions of the plates are serrated as at 18, 40 see Figs. 3 and 6, for the engagement of the hardened serrated shoes 16 and blocks 17 to prevent slipping, positioned in the said T-slots 12—12. It will also be noted that the remaining undersurface 19 of these plates which fit on the top surface of the base are finished to closely fit the said top surface of the base and to which they are secured by screws 15.

The shoes 16, see Fig. 3, are in the form of nuts and are small enough to be shifted longitudinally in the slots when the clamping screws are loosened whereas the blocks 17 are not serrated but have a finished upper surface to engage the undersurface of the central or intermediate jaw C, adapted to be inserted in the 55

T-slots from the end of the bed and adjusted thereon for positioning.

This yoke D is fixedly attached to the bed by means of screws 20 that extend through opposite end portions of the yoke and engage shoes 16 positioned one in each T-slot 12. An adjusting screw 21 is threadably mounted in the yoke and is provided with a collar 22 that is enclosed in a pocket of the clamping jaw B and covered by a steel plate 23 secured thereto by screws 24 and provided with a V-groove 25. This jaw B is slidably mounted on the base guided by the T-slots and provided, as shown in Fig. 3, with a block 17 positioned in the T-slots and attached to the jaw by screws 26 and which is adapted to be moved backward and forward in the slots by the operation of the clamping screw.

The jaw A is mounted on the rear end of the base and secured thereto by clamping screws 27 that extend through opposite side portions of the jaw and into the T-slots and threadably engages the shoes 16 whereby the said end jaw is securely though adjustably attached to the base. This jaw like those previously mentioned has a hardened plate 28 secured to its face by means of screws 29 and is further provided with vertical V-grooves 30 to insure firm engagement of the work piece.

The attachable intermediate jaw C shown in Figs. 2 and 3 is in a sense a floating jaw since it is not firmly secured to the bed but may be slipped along and positioned where desired as between the end jaw and the clamping jaw. It is provided with hardened steel plates 31 on opposite faces and secured thereto by screws 32. The said jaw is slidably held in position through the blocks 17 which are secured to the jaws by screws 26 and are longitudinally adjustable in the T-slot since it has no serration to engage those of the plates 13-13 and 14.

Inasmuch as my improved vise has been designed for use upon machine tools, such as milling and drilling machines, it will be understood that its particular application in this respect is for supporting one or more work pieces usually in spaced relation, for milling, drilling or tapping different classes of work and in this connection it is also desirable to provide for the use of suitable jigs and fixtures whereby the tools may be accurately set and used to the best advantage. My vise is accordingly well adapted for the use of the above class of fixtures and although the latter necessarily varies somewhat as to design it will be seen from Fig. 4 of the drawings that a simple form of fixture to be used for drilling or tapping can be applied to advantage and as will be noted comprises an L-shaped member 33 whose depending slotted portion 34 is secured to the back jaw A by means of a screw 35. To the top portion of this angle piece is adjustably secured an arm 36 by means of a screw 37, the forward end of the arm being adapted to hold a guide bushing 38 through which a drill is guided to the work piece, not shown.

In Fig. 5 I have shown a new type of multiple jig bushing plate attachment 39 adapted for gang drilling. As will be seen it carries a series of bushings 38 in spaced relation and the plate 39 as a whole is adapted to be attached to the top of the angle piece 33 by means of several screws 37 positioned one in each slot and engaging tapped holes in the angle piece so that the line of bushings will be disposed crosswise of the vise above the space between the members B and C.

Having thus described my invention what I claim and desire to secure by Letters Patent is:

1. A vise of the class described, comprising a base having longitudinal slots in the top portion, attached serrated plates covering side portions of said slots, a clamping jaw slidably mounted on the plates and guided by the slots, a clamping screw mounted on the base and having a collar on its forward end, said collar being rotatably mounted in said clamping jaw, an end jaw adjustably attached through the slots to the top portion of the base, a serrated shoe to engage the serrations of the plates, a clamping screw connecting the jaw and shoe, and steel plates secured to the front side portions of the jaws. 15

2. A vise of the class described, comprising a base having longitudinal slots in the top portion, plates covering side portions of said slots, a clamping jaw slidably mounted on the base and guided by the slots, a clamping screw mounted on the base and engaging said clamping jaw, an end jaw adjustably attached through the slots to the top portion of the base, and an attachable central floating jaw slidably mounted upon the bed and guided by being connected to the T- 25 slots for adjustment between the two previously mentioned jaws.

3. A vise of the class described, comprising a base having longitudinal T-slots in its top portion, the overhanging underportions of the T-slots 30 being serrated, a yoke covering one end portion of the base and slots, shoes and screws for adjustably securing the yoke to the T-slots and base, a clamping jaw slidably mounted on the base adjacent the yoke and guided by the T-slots, 35 and a clamping screw threadably mounted in the yoke and engaging the movable clamping jaw for adjustment of the latter.

4. A vise of the class described, comprising a base having longitudinal T-slots in its top portion, 40 the overhanging underportions of the T-slots being serrated, a yoke covering one end portion of the base and slots, shoes and screws for adjustably securing the yoke to the T-slots and base, a clamping jaw slidably mounted on the base 45 adjacent the yoke and guided by the T-slots, a clamping screw threadably mounted in the yoke and having a collar on its forward end, said collar being rotatably mounted in said clamping jaw, a steel plate secured to the face of the clamping jaw, an end jaw adjustably attached to the T-slots. 50

5. A vise of the class described, comprising a base having longitudinal slots in the top portion, plates covering side portions of said slots, an end jaw mounted on an end portion of the base, a yoke mounted on the opposite end portion of the base, a clamping jaw on the base adjacent the yoke, a clamping screw mounted in the yoke and engaging the clamping jaw, the overhanging 60 underportions of the plates covering the side portions of said slots being serrated, serrated shoes positioned in the T-slots to releasably engage the serrations on the plates and screws in the yoke and in the end jaw to engage said shoes to secure 65 the yoke and jaw to the base.

6. A vise of the class described comprising a base having a longitudinal T-slot in the top portion and openings from the T-slot out through the sides of the base, the overhanging portions 70 of the T-slot being serrated on their underside, serrated shoes adjustably mounted in the T-slot to engage the serrations thereof, jaws mounted for longitudinal adjustment on the base and carrying binding screws to engage the shoes in 75

the slots to secure the jaws in position, a slidable clamping jaw also mounted on the base, and a clamping screw mounted for the operation of the clamping jaw.

5 7. A vise of the class described, comprising a base, a back jaw adjustably secured to the base, a clamping jaw adjustably mounted on the bed for operation to and from the back jaw, a clamp-

ing screw mounted for operating the clamping jaw, a floating jaw also mounted upon the bed intermediate of the back jaw and the clamping jaw, and hardened steel plates secured to the face of the said jaws one having a horizontal V-groove and the other a vertical groove formed in the face thereof.

5 NEWMAN M. MARSILIUS.
